Attorneys.

UNITED STATES PATENT OFFICE.

HOWARD R. RAPER, OF ALBUQUERQUE, NEW MEXICO.

DENTIST'S HOLDER FOR FILM PACKS.

Application filed March 15, 1922. Serial No. 543,840.

To all whom it may concern:

Be it known that I, HOWARD R. RAPER, a citizen of the United States, residing at Albuquerque, in Bernalillo County and State of New Mexico, have invented new and useful Improvements in Dentists' Holders for Film Packs, of which the following is a specification.

This invention relates to a holder, the function of which is to hold a radio-sensitive film pack in position in the mouth to enable X-ray pictures of the teeth to be made. It is a common practice to have the patient hold the film pack in his mouth with his fingers, but this method is very unsatisfactory because it frequently results in imperfect radiographs due to the fact that the film is not held in the best position with relation to the tooth or teeth which are to be radiographed.

The general object of the invention is to produce a simple holder for this purpose which will operate to hold a film at any point in the mouth and which is so constructed as to insure that the film will be properly positioned behind the tooth or teeth to be radiographed; also to provide simple means for yieldingly holding or pressing the film pack against the gum and to provide simple means for adjusting this pressure to adapt the holder to operate effectively at different points in the mouth; also to provide special means for regulating the height of the film pack with respect to the teeth radiographed; also to provide the holder with a special construction which will insure a clear radiograph being made of the entire length of the tooth; and to provide a construction for the holder which will insure its being properly aligned and rigidly held between the teeth.

Another object of the invention is to provide means to facilitate the placing of the holder in the patient's mouth.

Further objects of the invention will appear hereinafter.

The invention consists in the novel features, and in the general combination of parts to be particularly described herein-after, all of which contribute to produce a simple and efficient dentist's holder for film packs. A preferred embodiment of my invention will be particularly described in the following specification, while the broad

scope of my invention will be pointed out in 55 the appended claims.

In the drawing,

Figure 1 is a vertical section through a holder embodying my invention and illustrating the same as in operation when taking a radiograph of an incisor of the upper jaw;

Figure 2 is a side elevation showing the same holder but representing it as applied for taking a picture of a molar or bicuspid 65 of the lower jaw;

Figure 3 is a plan of the holder and illustrating means which I may provide to facilitate its being placed in the patient's mouth by the dentist;

Figure 4 is a rear elevation of the holder with the film pack in place;

Figure 5 is a bottom plan of the holder shown in Figure 4;

Figure 6 is a view similar to Figure 4 but showing the film pack secured in place with its longitudinal axis vertical instead of horizontal;

Figure 7 is a vertical section through a holder and illustrating another embodiment 80 of the invention;

Figure 8 is a side elevation of a holder showing still another embodiment of the invention; and

Figure 9 is a rear elevation of the resilient part of the holder shown in Figure 8 and representing the same removed from the body of the holder.

Referring more particularly to the parts 1 represents the body of the holder (see Figures 1 to 3). This body is constructed so as to be supported in any suitable manner by the teeth of the patient. It is also provided with means for holding the film pack within the mouth and behind the teeth which are to be radiographed. The film pack 2 is preferably secured to the body 1 by means of a slot 3 formed in the body and which receives the edge of the film pack. The means for holding the film also includes a member for yieldingly engaging the side of the film in such a way as to hold it against the gum. This means may be constructed of metal if desired, but I prefer to construct it in the form of a resilient and yielding tongue 4 of soft rubber or similar material. This tongue is mounted in a socket 5 formed in the body so that the tongue extends transversely to

the long axis of the body 1. I also prefer to secure the film pack in the slot by means of a small screw 6 which is threaded in the body and passes through the socket 5 so that it operates to hold the tongue 4 in place, the inner end of the screw lying in the slot in such a way as to clamp the film pack within the slot. I prefer to use an undercut or an inclined slot because this facilitates holding the film pack in the desired relation to the tooth. Incidentally this assists in securing the pack in the slot, the slot being inclined in such a direction that the bottom of the slot lies beyond the tip of the screw; hence the tightening up of the screw will tend to seat the film pack in the bottom of the slot, rather than force it out of the slot. The extension of the body 1 which lies on the side of the film pack opposite to the socket 5 is constructed so as to be held between the teeth, see Figure 2 which represents the holder set in place with a film pack for taking the radiograph of a lower molar.

It is preferable to provide means for regulating the depth of the slot, or its virtual depth, and this I accomplish by providing a removable filler in the form of a screw 7 which is received in a threaded opening drilled through the block or body at the bottom of the slot. Figure 1 shows this filler in place, while Figure 2 shows the slot with the filler removed.

In order to insure perfect clearness of the radiograph in the vicinity of the outer end or face of the teeth I construct the body at the point where it engages the teeth of a radio-lucent or radioparent material. By that I mean a material through which the Röntgen rays will pass freely. In order to accomplish this and also provide additional means for increasing the virtual depth of the slot I provide the face of the body 1 which comes against the teeth to be radiographed, with a removable slab 8 of radio-lucent material such as celluloid, amber or similar material. If desired, the entire body can be constructed of celluloid or similar material, or the body may be of metal and the slab of radio-lucent material attached in place by means of a dove-tailed groove 9. I provide a set screw 10 in the block for securing the slab in place. The inner edge of this slab is in substantial alignment with the wall of the slot so that it constitutes a continuation of the slot wall and virtually increases the depth of the slot. I provide several slabs of different thickness and attach the slab in place that gives the desired depth for the slot. The object in varying the depth of the slot in this way is, of course, to regulate the position of the film pack with respect to the tooth which is being radiographed.

In Figure 1 I illustrate a slab 11 that does not increase the depth of the slot but its up-

per face is simply flush with the face of the block or body 1.

The body of the film is positioned in the mouth in the manner indicated in Figures 1 and 2 so that the film pack is held against the inner face of the gum, the X-rays passing in the general direction indicated by the arrows.

Suitable means is provided for adjusting the resilient means or tongue 4 so as to alter its relation with respect to the body 1. For this purpose I may provide the body 1 with a transverse pin 12 (see Figures 2 and 3). This pin passes through the body and through the material of the tongue within the socket. The pin may be put in place with the tongue in its normal position projecting at right angles to the direction in which the body 1 extends, that is to say, the tongue projecting straight out from the socket, but if desired, the pin may be removed and the tongue bent forward or toward the position which the tooth will occupy, and the pin can then be replaced in the tongue. This will have the effect of giving a forward adjustment or tilt to the tongue and will enable it to back up or support the film where the face of the gum is more nearly in a plane at right angles to the axis of the body 1. A film pack 2 may be applied with its longitudinal axis horizontal or with its longitudinal axis vertical (see Figures 4 and 6).

The body 1 is preferably constructed so that it may be held between the patient's teeth as in biting and the construction is such as to insure that when held in this way the act of biting will not tend to tilt the holder out of position. In this connection it should be understood that the upper face of the block 1 as shown in Figures 1 and 4 seats against the upper row of teeth. In Figure 4 the line 13 represents the line of bite of the upper teeth and the line 14 represents the line of bite of the lower teeth. In order to prevent the lower teeth from tilting the body I provide this side of the body with a rounded or bevelled face 15. In this way I avoid forming any corners on the body which could be engaged by the teeth in the biting line 14 and hence there is less tendency to tilt the body and film pack, for the reason that the force or pressure is exerted by these teeth more nearly in the middle plane of the body. It should be understood, however, that in Figure 4 the lines 13 and 14 refer to the positioning of the device to take a radiograph of a molar. In order to facilitate the holding of the device to take the radiograph of an incisor as in Figure 1, I provide the rounded face of the body with a plurality of score lines or grooves 16 which may be engaged by the bite of the incisors. In other words if the line 17 of Figure 6 represents the biting line of the lower teeth,

this biting line would lie substantially at the bottom of one of the notches 16, while the biting line 18 would represent the position of the upper incisors as they rested on the 5 upper face of the body.

Instead of constructing the tongue 4 of soft rubber I may construct it of a metal spring. This may be accomplished as illustrated in Figure 7 by providing a removable 10 block 19 which will fit into the socket 5 when the tongue 4 has been removed. This block 19 would be drilled to permit the clamping screw 20 to pass through it to clamp the film pack 21 in position. The upper side of this 15 block carries a column or tongue 22 which may be in the form of a coil spring. This coil spring tends to assume a position in which its axis would lie at right angles to the axis of the screw 20, but when engaged 20 by the pack 21 it exerts a yielding pressure against the face of the film pack and assists in holding it against the gum.

If desired the yielding tongue may have the features illustrated in Figures 8 and 9 25 in which a bifurcated wire spring 23 has its forks 24 received in openings in the upper face of a small block 25 which fits into the socket of the body. These forks 24 are each provided with a coil 26 giving considerable resiliency to the upper end of the tongue which engages the rear face of the film pack 27.

In order to facilitate the placing of the holder and film pack in position I may provide the block with a pair of adjacent openings or sockets 28 (see Figure 3) which may receive the tines 29 of a fork carried on a suitable handle 30.

An additional advantage arises from the 40 use of amber or celluloid on one side of the body by reason of the fact that such a material is slightly resilient and operates to enable the teeth to hold the holder more rigidly with a given amount of pressure of 45 the teeth. In other words, a better effect arises than that which occurs when both rows of teeth bite against metal.

It is understood that the embodiment of the invention described herein is only one 50 of the many embodiments my invention may take, and I do not wish to be limited in the practice of my invention, nor in my claims to the particular embodiment set forth.

What I claim is:

55 1. A holder for a radio-sensitive film pack having a body constructed to be supported by the teeth of the patient, means carried by said body for holding the edge of the film pack, and resilient means also carried by the 60 body for engaging the inner side of the film pack in the free portion thereof beyond said holding means for holding the film pack against the gum.

2. A holder for a radio-sensitive film pack 65 having a body constructed to be supported

by the teeth of the patient, said body having means for securing the edge of the film pack thereto, and means also carried by said body and extending beyond the same for yieldingly engaging the back side of the pack 70 when the holder is in operative position to hold the film pack against the gum.

3. A holder for a radio-sensitive film pack having a body constructed to be held between the teeth by the bite of the patient, said body having means for carrying and holding the film pack, including a resilient member 75 extending laterally from the body and constructed to yieldingly engage the non-sensitive side of the film pack for holding the 80 film pack against the gum.

4. A holder for a radio-sensitive film pack having a body constructed to be held between the teeth of the patient, and having a 85 transverse slot for holding the edge of the film pack, and means for adjusting the depth of the slot.

5. A holder for a radio-sensitive film pack having a body constructed to be held between the teeth of the patient, said body having a transverse slot cut in a plane inclined 90 to the direction in which the body extends, and an engaging member carried by the body and co-operating therewith to hold the film in the slot.

6. A holder for a radio-sensitive film pack having a body constructed to be held between the teeth of the patient and having a transverse slot to receive the edge of the film pack, means carried by said body for holding the film pack so as to extend laterally from the body, said body having a detachable X-ray translucent slab on its side on which the film pack extends from the body, 100 the inner edge of said slab being substantially in alignment with a wall of said slot.

7. A holder for a radio-sensitive film pack having a body constructed to be held by the bite of the patient, means carried by the body for holding a film pack so as to extend 110 behind the teeth, said body having a substantially flat face on the side thereof adjacent to the direction in which the film pack extends and having a substantially rounded 115 surface on the opposite side, the rounded surface whereof is positioned to be engaged by the teeth on that side, to prevent tilting the body out of position.

8. A holder for a radio-sensitive film pack having a body constructed to be held between the teeth by the bite of the patient, said body having means for carrying and holding the film pack including a resilient member 120 extending laterally from the body constructed to yieldingly engage and exert pressure on the inner side of the film pack 125 when carried by said slot, and means for adjusting the position of said member with respect to the body.

9. A holder for a radio-sensitive film pack 130

having a body constructed to be held between the teeth by the bite of the patient, said body having means for carrying and holding the film pack including a member 5 composed of soft rubber extending laterally from the body and constructed to engage the inner side of the film pack.

10. A holder for a radio-sensitive film pack having a body constructed to be held 10 by the bite of the patient, means carried by the body for holding a film pack so as to extend behind the teeth, said body having a substantially flat face on the side thereof adjacent to the direction in which the film pack 15 extends and having a rounded face on the opposite side, said rounded face operating when engaged by the teeth on that side, to prevent tilting the body out of position, said rounded face having transverse grooves 20 therein adapted to be engaged by the incisors when the holder is held at the front of the mouth.

11. A holder for a radio-sensitive film pack having a body constructed to be held

between the teeth by the bite of the patient, 25 said body having a transverse slot for receiving the edge of the film pack, and a clamping screw mounted in said body so that its end may project into the slot, the said slot being inclined in such a direction 30 that the bottom of the slot lies beyond the end of the screw, whereby the tightening of the screw tends to seat the edge of the film at the bottom of the slot.

12. A holder for a radio-sensitive film 35 pack having a body constructed to be held between the teeth by the bite of the patient, said body having a transverse slot for receiving the edge of the film pack, and a resilient member for supporting the film pack 40 extending laterally from the body and secured thereon at a distance from said slot to permit the film pack to slant toward said member before the latter is engaged by the inner side of the film pack. 45

In testimony whereof, I have hereunto set my hand.

HOWARD R. RAPER.
